CLAIM

I claim the ornamental design for a beverage can, as shown and described.

DESCRIPTION

FIG. 1 is a perspective view of the beverage can, showing my new design;

FIG. 2 is a front side thereof;

FIG. 3 is a rear side thereof;

FIG. 4 is a right side view thereof;

FIG. 5 is a left side view thereof; and,

FIG. 6 is a top plan view thereof.

1 Claim, 6 Drawing Sheets

FIG. 1

FIG. 2

FIG. 3

FIG. 4

FIG. 5
